UNITED STATES PATENT OFFICE.

HENRY W. LOHOEFENER, OF KANSAS CITY, MISSOURI, ASSIGNOR OF ONE-HALF TO
EARL L. WINGBLADE, OF KANSAS CITY, MISSOURI.

VALVE-SPRING COMPRESSOR.

Application filed December 20, 1926. Serial No. 156,034.

This invention relates to valve spring compressing tools and forms a continuation in part of my application for Patent Ser. No. 71,347, filed November 25, 1925, and has for 5 one of its objects to produce a compressing tool which simultaneously engages the head of the valve and the spring to prevent upward movement of the valve when force is exerted to compress the spring.

10 Another object is to produce a tool of the character outlined which is of adjustable nature and may be utilized on practically all engines of the poppet valve type and by means of which the operator may maintain a spring 15 compressed with one hand while he pulls the spring retaining pin with his other hand.

A further object is to provide a valve spring compressor which is of simple, strong, durable and inexpensive construction; and 20 in order that it may be fully understood, reference is to be had to the accompanying drawing, in which:

Figure 1 is a side elevation of the tool in operative relation to a valve, the compressed 25 position of the spring being shown by dotted lines.

Figure 2 is a top plan view of the tool.

Figure 3 is a section on the line III—III of Figure 1.

30 Figure 4 is a reduced edge view of the tool.

Figure 5 is a broken sectional view of a tool of slightly modified character.

Figure 6 is a section on the line VI—VI of Figure 1.

35 In the said drawing, where like reference characters identify corresponding parts in all of the figures, 1 indicates a valve head, 2 the valve stem, 3 the spring for closing the valve, and 4 the customary recessed washer 40 on which the end of the spring rests, said washer being held in position by a pin (not shown) within the recess of the washer.

The tool of the invention comprises a relatively L-shaped valve member 5 adapted to 45 engage the valve head 1 at one of its ends, and secured to the other end of said valve engaging member or formed integrally therewith is a guide 7 spaced from the valve member, said parts being secured in the device 50 as illustrated by providing the guide with a pair of ears 8 adapted to be engaged in notches in the side edges of the member 5 as shown by the drawing.

Slidably received between the member 5

and the guide 7 is a spring engaging L-shaped member 10 having its operating end terminating in or provided with a suitable fork 11 for direct engagement with the spring washer 4. In this connection it is desirable to point out that the fork 11 may be removably secured by 60 a pin 11^a whereby various sizes of forks may be substituted according to the valve mechanism.

The member 5 is formed at a point above the guide 7 with a laterally projecting ear 12 bent as at 13 to alignment with the sliding member 10, and pivoted to said ear is an operating lever 14 having its end bent as at 15 to accommodate an element or link 16 connected at one end to the lever 14 and at its other end to a bolt 17 which is inserted in position in the member 10 by being passed through an opening 17^a in the member 5 and having its head received within a countersunk portion around each of a series of adjusting holes 18 formed in the end of the sliding member 10.

It will be apparent that by choosing the proper adjusting holes 18 in the sliding member 10, the operator can readily accommodate the tool to engines of greatly varying proportions, and that after the ends of the tool have been engaged with the valve parts, downward pressure on the lever 14 will effect compression of the valve spring 3. When 85 compressed, the operator can maintain the position of the spring with one hand while he uses the other hand in withdrawing the valve pin (not shown).

In the device as illustrated in Figure 5, 90 no method of adjusting the tool to different engines is provided other than the very limited degree of radial movement of the operating lever. In said figure, the valve head engaging member 19 is tubular and the 95 valve spring engaging member 20 slides therewithin, being connected to the operating lever 21 by means of an element or flexible connection 22 which passes through an opening 23 formed in the member 19. The modified form of device is operated in all respects similar to that of the adjustable device above-described.

From the above description, it will be apparent that while I have described and illustrated the preferred embodiment of the invention, it is to be understood that I reserve 105 the right to make all changes properly falling

within the spirit and scope of the appended claims.

I claim:—

1. A valve spring compressor comprising a valve engaging member having at one end a guide and being formed intermediate its ends with a laterally projecting ear, a spring engaging member slidably received at one end in the guide of the first member, a lever pivoted to said projecting ear, and an element connecting said lever and spring engaging member.
- 10 2. A spring compressor comprising a valve engaging member having at one end a guide and being formed intermediate its ends with a laterally projecting ear, a spring engaging

member slidably received at one end in the guide of the first member and having its other end in alinement with the free end of the valve engaging member, a lever pivoted to said ear, and an element connecting said lever and spring engaging member.

20 3. A valve spring compressor comprising a valve engaging member, a spring engaging member slidably arranged therein, and operating means for said members extending within the first-named member and including a lever for drawing said members toward each other.

25 In witness whereof I hereunto affix my signature.

HENRY W. LOHOEFENER.
